UNITED STATES PATENT OFFICE.

LEWIS FRITZ, OF CHICAGO, ILLINOIS.

PICTURE FRAME.

1,421,448.

Specification of Letters Patent.

Patented July 4, 1922.

Application filed November 30, 1921. Serial No. 518,784.

To all whom it may concern:

Be it known that I, LEWIS FRITZ, a citizen of the United States, and a resident of the city of Chicago, county of Cook, and State 5 of Illinois, have invented certain new and useful Improvements in Picture Frames, of which the following is a specification.

My invention relates to improvements in picture frames, and has for its principal object the provision of an improved construction 10 of this character which will be simple in structure and economical in manufacture.

A further object of my invention is the provision of a construction of a picture frame which will be dust-proof and airtight.

A still further object of my invention is the provision of a construction of a picture frame whereby a number of picture frame 20 blanks of various sizes can be stamped or struck from a single piece of material without wasting any great quantity of the material.

Other objects will appear hereinafter.

The invention consists in the combinations and arrangements of parts hereinafter described and claimed.

The invention will be best understood by reference to the accompanying drawings 30 forming a part of this specification, and in which,

Fig. 1 is a face view of my improved picture frame,

Fig. 2 is a blank from which my improved picture frame is formed,

Fig. 3 is a rear elevational view of my improved picture frame,

Fig. 4 is a fragmentary detail view of the same taken substantially on line 4—4 of 40 Fig. 3, and

Fig. 5 is a sectional detail view of the same taken substantially on line 5—5 of Fig. 3.

The preferred form of construction, as 45 illustrated in the drawings, comprises a picture frame blank 9 which is stamped or struck from a single piece of material, the outlines of said blank being similar to that illustrated in Fig. 2 of the drawings, and 50 when formed, in the manner hereinafter set forth, constitutes a picture frame 10'. The construction illustrated in the drawings constitutes the preferred form, however the

frame can be cast or made of wood or any other material suitable for the purpose. In 55 Fig. 2 of the drawings, 10 and 11 indicate the face portions of the picture frame 10' and 12 and 13 indicate the side and end edges of the same. The reference characters 14 and 15 indicate lateral flanges which are 60 formed integral with the edges of the face portions 10 and 11 of the picture frame. The side and end edges 12 and 13 and the lateral flanges 14 are bent in the manner shown in Fig. 5 of the drawings, the construction being such as to provide recesses 65 16 which extend longitudinally with respect to the sides of a frame and a recess which extends along the lower end of the frame as shown in Fig. 3. The edges 14' of the lateral 70 flanges 14 are bent back upon the side lateral flanges, as shown in Fig. 5, to obviate sharp edges. In order to provide a tight joint at the points of juncture of the lateral flanges 14, I miter the ends of the lateral flanges, 75 as at 17, Fig. 3. If desired, the ends of the lateral flanges 14 can be made to overlap each other so as to afford a stronger joint at the points of juncture. Formed on the edges 17' of the opening 23' of the frame 80 are lateral flanges 18 which are bent back upon the face portions, so as to obviate sharp edges. Positioned between the lateral flanges 18 and the back of the face portions 10 and 11, and extending around the frame, 85 is a reenforcing member 19 which is in the form of a twisted wire, as illustrated in Figs. 1 and 5. The purpose of the reenforcing wire 19 is to prevent the inner ends 17' of the face portions 10 and 11 from being 90 dented or otherwise disfigured when the picture frame blank 9 is stamped or struck from a light piece of material. The lateral flange portion 15 is bent in the manner illustrated in Fig. 4, so as to provide a shoulder 95 20, as shown in Fig. 4, under which the upper edge 21 of the back 22 of the frame is adapted to engage, said back 22 being slidably mounted in the recesses 16. The back 22 constitutes the material removed from 100 the picture frame opening 23' of a picture frame blank somewhat larger than the picture frame blank illustrated in the drawings. The upper edge 21 of the back 22 is bent back upon the back 22 in the manner 105 illustrated in Fig. 4, so as to reenforce the

edge 21 which engages the shoulder 20. The central portion of the reenforced edge 21 is curved outwardly, from the back 22, as at 23, Fig. 4, to provide a lip which can be 5 easily grasped with the fingers to facilitate removing of the back from the recesses 16. A suitable chain or wire member 25 is secured by any suitable manner to the side 10 lateral flanges 14 to facilitate hanging the picture frame with its several parts properly mounted together on a wall or the like. In mounting a picture or the like in my improved frame, a glass 24 is mounted in the recesses 16, and the picture or photograph, 15 not shown, is inserted in back of the glass. The back 22 is then mounted in the recesses 16, the upper reenforced edge 21 being pressed downwardly under the shoulder 20, as illustrated in Fig. 4, releasably locking 20 the back in position. In the construction as herein set forth, I provide a picture frame which is economical in manufacture and which when formed, and its several parts fitted together, will be dust-proof and in- 25asmuch as the several parts are tightly fitted together, in the manner herein set forth, the picture frame will also be air-tight, thus preserving the life of the picture or photograph or the like, mounted in the frame.

30 Another advantage of a construction of a picture frame as described and illustrated, is that any number of picture frame blanks, such as illustrated in Fig. 2, of various sizes, can be struck from the same piece of 35 material by substituting the material removed to provide the picture frame opening 23' for the back of a smaller picture frame, or by stamping or striking a picture frame blank from the said material, which 40 of course, will be smaller than the size of the picture frame blank from which the material is removed.

While I have illustrated and described the preferred form of construction for carrying 45 my invention into effect, this is capable of variation and modification without departing from the spirit of the invention. I, therefore, do not wish to be limited to the precise details of construction set forth, but 50 desire to avail myself of such variations and modifications, as come within the scope of the appended claims.

Having described my invention, what I 55 claim as new and desire to secure by Letters Patent is:

1. An article of the class described comprising a frame struck from a single piece of material and having an opening therein, there being lateral flanges on the edges of 60 said frame and the edges of said opening being bent inwardly upon said frame; a back removably positioned between said frame and the flanges formed on the edges thereof; and a reinforcing member 65 surrounding said opening and arranged be-

tween the flanges on the edges of said opening and said frame.

2. An article of the class described comprising a frame, there being lateral flanges on said frame and bent inwardly thereupon 70 forming channels; a back removably positioned in said channels; an upwardly turned lip formed on said back to facilitate removing said back from said channels; and a shoulder transversing said frame at the entrance thereof for releasably holding said back against removal from said frame.

3. In a picture frame comprising a frame blank having a central opening therein and lateral flanges formed on the edges of said 80 blank and the edges of said opening being bent inwardly upon said blank; a back positioned between said blank and the flanges on the edges thereof; and a lateral shoulder at one end of said blank adapted to releasably 85 hold said back in such position.

4. In a frame for pictures or the like, the combination with a frame blank struck from a single piece of material, there being recesses formed on said frame; a lateral stop 90 transversing said frame at the entrance thereof; a back for said frame, one of the edges of said back being bent upon the body portion thereof, said bent portion being arranged and adapted to engage under said 95 shoulder; and an upwardly turned portion on said bent portion of said back to facilitate disengaging said bent portion from said shoulder.

5. A picture frame comprising a channel 100 shaped frame; a back slidably mounted in said frame, the upper end portion of said back being bent back upon the body thereof; a lateral flange at the entrance of said frame, said flange being bent inwardly to 105 form a stop for said back; a lip formed on said bent portion of said back to facilitate the removing of said back; lateral flanges formed on the inner edges of said frame and bent inwardly thereupon; and a twisted wire 110 member arranged between said inner flanges and said frame for reinforcing the edges of the opening thereof.

6. In a picture frame comprising a channel shaped frame and a back for said frame 115 having an edge bent back upon the body thereof; a transverse shoulder at the entrance of said frame and extending laterally therefrom adapted for engagement with said bent edge for releasably holding said back 120 against removal from said frame; and means on said bent edge to facilitate the removing of said back from said frame.

7. A picture frame including a blank having a central opening therein; lateral flanges on the edges of said blank and the edges of said opening being bent inwardly 125 upon said blank; and a back releasably held in recesses formed between said blank and the flanges on the edges thereof.

8. A picture frame including a blank struck from a single piece of material and having an opening therein; lateral flanges on the edges of said blank, the edges of said flanges being bent inwardly thereupon; lateral flanges on the edges of said opening; and a back removably carried by said blank.

In testimony whereof I have signed my name to this specification in the presence of two subscribing witnesses.

LEWIS FRITZ.
